UNITED STATES PATENT OFFICE.

MARY A. BROWN, OF PLAINFIELD, NEW JERSEY.

SEWING-CABINET.

SPECIFICATION forming part of Letters Patent No. 788,749, dated May 2, 1905.

Application filed December 24, 1903. Serial No. 186,458.

To all whom it may concern:

Be it known that I, MARY A. BROWN, a citizen of the United States, residing at Plainfield, in the county of Union and State of New Jersey, have invented an Improvement in Sewing-Cabinets, of which the following is a specification.

My invention relates to a cabinet for sewing utensils for women's work, and especially to those portions of the cabinet that are designed for spools of thread and appliances therefor, for pins and needles, and adjacent parts for the reception of work, and my invention comprises a novel combination and arrangement of convenient and handy parts leading to the consummation of a complete device.

I prefer to employ a cabinet in the well-known form of a roll-top desk having a platform against which said top closes, with series of pigeonhole boxes or drawers above the platform and under the top and a series of drawers in the lower portion of the cabinet above the floor. I employ in carrying out my invention as applied to such a cabinet a sliding work-board parallel to the fixed platform of the cabinet and appreciably below the same. Intermediate of these parts and at the front of the cabinet is a hinged flap perforated and carrying series of thread-tension devices and a central cutter adapted for severing the threads. In the front of the cabinet and directly back of the flap are longitudinally-arranged spool-receptacles, each having flaps providing for the entrance of spools into the receptacles and then closing up the same, and in these flaps there are series of perforations and companion threadways. The perforations and tension devices aline, so that the threads draw straight, are held, and may be independently severed. Beneath the fixed platform and behind the receptacles for spools is a space separated by hinged partitions to which access is had through an opening in the fixed platform. This opening is normally closed by a removable box fitting therein and having a cover, which when closed down alines with and completes the surface of the fixed platform and on the under surface of which is preferably secured a cush-

ion for loose pins and needles. This box and the divided space beneath the platform and surrounding the same partake of the nature of secret compartments known only to the user.

In the drawings, Figure 1 is a vertical cross-section through so much of the cabinet as illustrates the features of my invention. Fig. 2 is a plan view and partial section above the platform and through one of the spool-receptacles. Fig. 3 is a front elevation broken away with the flap holding the tension devices turned down so as to show the interior flaps. Fig. 4 is an elevation in enlarged size of a portion of the flap and tension devices and the central bar for severing the thread. Fig. 5 is an elevation at the back of one of the tension devices alone, and Fig. 6 is a plan of the parts shown in Fig. 5. Fig. 7 is a perspective view of my improved cabinet with a portion of the front flap and of the back removed.

The cabinet is provided with sides *a a'*, a back *b*, a top frame *b'* with drawers *c* in the lower portion above the floor, with a fixed platform *d*, and the top frame *b'*. I prefer to construct, as hereinbefore stated, with a roll-top and with pigeonholes and small drawers of usual construction. At an appreciable distance below the fixed platform *d* is a work-board *e*, that may be drawn forward and the major portion of which brought outside of the cabinet. This moves on a slideway 2. This board *e* when drawn out serves to rest or cut work upon, and it may be provided with a rule showing inches or centimeters marked upon or let into the surface.

At the front of the cabinet and in the space bounded by the under surface of the fixed platform *d*, the sides *a a'*, and the upper surface of the work-board *e* I place a hinged flap *f*, pivotally mounted to the cabinet, preferably by hinges 3 at the ends, which substantially are pins passing through the sides *a a'* into the ends of the flap. This hinged flap is provided with one or more rows of spaced-apart tension devices *f'*, set into perforations in said flap. As shown especially in Figs. 4, 5, and 6, each of these tension devices comprises a front plate 4, a slotted hub 5, and a yoke-spring 6, the spring being held to the hub by a set-screw. (Shown in Figs. 5 and 6.) This

hinged flap f is provided with a longitudinal central bar f^2 , having a longitudinal central groove to receive the cutting-blade f^3 and series of cross-notches 7, which agree in number and in position vertically with the several tension devices of the series.

In the space between the fixed platform d and the work-board e and directly back of the hinged flap f are spool-receptacles formed by 10 a back strip 8, a base-strip 9, and a central strip 10, preferably of wood and securely connected together and in position in the cabinet. A flap g is hinged to the base-strip 9 at its lower edge and a flap h is hinged to the central strip 10 at its lower edge, so that the said flaps g and h may turn downward and outward from the spool-receptacles, providing for the entrance of the spools into the receptacles. Each of these flaps is provided with 15 perforations of elongated form and companion threadways cut through said flaps from the upper edges to the perforations. (See especially Fig. 3.) These perforations and threadways agree in number with the possible 20 number and location of spools in the receptacles, and in said receptacles the spools are placed on the peripheries of the ends, so that the axes of the spools are horizontal, (see 25 Figs. 1 and 2,) and when so placed the perforations and threadways come substantially 30 central with the respective spools and the threads as drawn off the spools can move along through the elongated perforations. The spools do not need any central rod or guide, as 35 the receptacles are only slightly larger than the spools and the spools rotate on their imaginary axes as the threads are drawn off. The threads pass through the perforations of the 40 flaps g h and through the apertures of the tension devices between the yoke-springs 6.

I prefer to place upon the outer surface of the flap f , adjacent to the tension devices, numbers that agree with the numbers of the threads being drawn through the tension devices, so 45 that the number of the thread may be known without any reference to the spool. The tension devices hold the respective threads and prevent accidental unwinding, and in use when a given length of thread from any particular 50 spool is drawn out the thread being from the top row of spools is moved down and if from the lower row of spools is moved up into the companion notch 7 of the central bar f^2 , and is so brought in contact with the cutting-blade 55 f^3 , which severs the thread. There is thus no breaking of the thread by hand and as the thread is cut short only a small length of thread is left exposed.

Beneath the fixed platform and behind the 60 receptacles for spools—that is, between the back 8, the horizontal partition i , (which is a prolongation of the part 9,) the fixed platform d , and the vertical partition i' and the sides a a' of the cabinet—there is a space in which are 65 placed the hinged partitions k k' . These par-

titions are hinged to the base or horizontal partition i . They are adapted to run from the front to the back of the cabinet and to turn down against the horizontal partition i toward the center and toward one another, 70 and they are largely held in position vertically, as shown in Figs. 1 and 2, by the presence of the box l , which fits in an opening in the fixed platform d at the back and is provided with a lid l' . When the box is in position and the 75 lid closed down, the box is supported upon the horizontal partition i and the surface of the lid alines with or is in the same plane with the upper surface of the fixed platform d . Any suitable device may be employed by means of 80 which the lid l' is grasped and raised, and the lid when raised may be the means by which the box is lifted out of the cabinet. On the under side of the lid is a cushion l^2 for loose pins and needles. The lid can be raised and 85 thrown back against the back of the cabinet and occupy a slightly backwardly-inclined position where it is self-supporting in use when the box is in the position shown in Figs. 1 and 90 2, or when the box is reversed and placed in the opening with the hinges of the cover toward the front of the cabinet the lid when raised may be turned back to rest flat upon the fixed platform in a horizontal position, as 95 shown in the perspective view, Fig. 7, in which the cushion is near the front of the cabinet. When the box is lifted out of the cabinet, access is obtained through the opening in the fixed platform d to the space beneath the same and for the movement of the hinged partitions 100 k k' , so as to give access to the inner spaces that they closed up when placed vertically. These divided spaces beneath the platform and surrounding the box partake of the nature of 105 secret compartments.

I claim as my invention—

1. In a cabinet, the combination with a receptacle for spools, of a flap providing for the entrance of the spools into the receptacle and having a series of apertures agreeing in number with the number of spools and through which apertures the threads of the spools pass, and a flap in the cabinet located outside of the aforesaid flap and containing a series of thread-tension devices agreeing with the number of 115 spools and through which the threads pass.

2. In a cabinet, the combination with a receptacle for spools, of a flap providing for the entrance of the spools into the receptacle and having a series of apertures agreeing in number with the number of spools and through which apertures the threads of the spools pass, and a flap in the cabinet located outside of the aforesaid flap and containing a series of tension devices agreeing with the number of 120 spools, and through which the threads pass, and a cutter-bar adapted for severing the threads.

3. In a cabinet, the combination with a receptacle for spools, of a hinged flap provid-

ing for the entrance of the spools into the receptacle and having a series of elongated apertures agreeing in number with the number of the spools, and through which the threads 5 of the spools pass and along which they may move as they are unwound, and a series of threadways formed in said flap from one edge and merging with the elongated apertures for bringing the threads into the elongated apertures, a hinged flap in the cabinet forward of the aforesaid flap, a series of tension devices in perforations in said flap agreeing in number with the number of the spools, and through which tension devices the threads are 10 drawn and a cutter-bar for severing the threads.

4. In a cabinet, the combination of a series of receptacles for spools, the one superimposed on the other, a hinged flap for each receptacle providing for the entrance of the spools into the receptacles, each flap provided with a series of elongated apertures agreeing in number with the number of the spools and through and along which the threads of the 15 spools pass as they are unwound and series of threadways formed in said flaps from one edge to and merging with the elongated apertures for bringing the threads into the elongated apertures, a hinged flap in the cabinet 20 forward of the aforesaid flaps and in a plane parallel therewith and in width extending over the width of the aforesaid flaps, series 25 of tension devices in perforations in the latter flap agreeing in position and in number with the number of the spools in said receptacles, and through which tension devices the threads are drawn, and a cutter-bar centrally located on the latter flap between the series of tension devices for severing the threads from the 30 spools in the respective receptacles.

5. In a cabinet, the combination with a receptacle for spools, of a hinged flap providing for the entrance of the spools into the receptacles and having a series of elongated apertures agreeing in number with the number of the spools and through which the threads of the spools pass and along which they may move as they are unwound, a hinged flap in the cabinet forward of the aforesaid flap, a series 45 of tension devices in perforations in said flap agreeing in number with the number of the spools and through which tension devices the threads are drawn and means for severing the threads.

55 6. In a cabinet, the combination of a horizontally -arranged receptacle for spools of varying sizes, extending across the front or forward portion of the cabinet in which the spools rest upon the peripheries of their ends with their axes in horizontal planes, three 60 sides of said receptacle being formed of fixed members, a hinged flap vertically placed and forming the inclosing member of said receptacle for confining the spools, the flap having a series of horizontally-placed elongated aper-

tures agreeing in number with the number of the spools and through which apertures the threads pass, and a series of companion threadways cut through the flap from the upper edge to and merging with the elongated apertures 70 for introducing the threads, and a second hinged flap forward of the aforesaid flap in a plane parallel therewith and forming the outer surface of the cabinet, and a series of tension devices placed in openings in the latter flap 75 agreeing in number with the apertures in the first-named flap and in line with the thread for applying tension to the threads as withdrawn.

7. In a cabinet the combination of a horizontally -arranged receptacle for spools of varying sizes extending across the front or forward portion of the cabinet in which the spools rest upon the peripheries of their ends with their axes in horizontal planes, three 80 sides of said receptacles being formed of fixed members, a hinged flap vertically placed and forming the inclosing member of said receptacle for confining the spools, the flap having a series of horizontally-placed apertures 85 agreeing in number with the number of the spools and through which apertures the threads pass, and a series of companion threadways cut through the flap from the upper edge to and merging with the elongated apertures 90 for introducing the threads, a second hinged flap forward of the aforesaid flap in a plane parallel therewith and forming the outer surface of the cabinet, a series of tension devices placed in openings in the latter flap 95 agreeing in number with the apertures in the first-named flap and in line with the thread for applying tension to the threads as withdrawn, and a longitudinal bar upon the outer flap, and a cutting-blade therein for severing 100 the threads.

8. In a sewing-cabinet having a top and back, the combination with a fixed platform having an opening therein near the back, of a removable, reversible box for sewing utensils 110 fitting the opening in the fixed platform, a support therefor below the fixed platform, so placed as to bring the top of the box on a level with the fixed platform, the parts being so arranged that the hinged top of the box may in 115 one position swing up against the back of the cabinet, and in the reverse position swing forward and lie flat on the fixed platform.

9. In a cabinet, the combination of a horizontally -arranged receptacle for spools of varying sizes extending across the front or forward portion of the cabinet in which the spools rest upon the peripheries of their ends with their axes in horizontal planes, three 120 sides of said receptacle being formed of fixed members, a hinged flap vertically placed and forming the inclosing member of said receptacle for confining the spools, the flap having a series of horizontally-placed apertures agreeing in number with the number of the spools 125 130

and through which apertures the threads pass, and a second hinged flap forward of the aforesaid flap in a plane parallel therewith and forming the outer surface of the cabinet, and 5 a series of tension devices placed in openings in the latter flap agreeing in number with the apertures in the first-named flap and in line with the thread for applying tension to the threads as withdrawn.

- 10 10. In a cabinet, the combination of a series of receptacles for spools, the one superimposed on the other and both receptacles extending across the front and forward portion of the cabinet, a hinged flap for each receptacle providing for the entrance of the spools into the receptacle, each flap provided with a series of apertures agreeing in number with the number of the spools and through which the threads of the spools pass as they are un-

wound, a hinged flap in the cabinet forward 20 of the aforesaid flaps and in a plane parallel therewith and in width extending over the width of both the aforesaid flaps, a series of tension devices in perforations in the latter flap agreeing in position and in number with 25 the number of the spools in said receptacles, and through which tension devices the threads are drawn, and means located on the outer surface of the latter flap between the series of tension devices for severing the threads from 30 the spools in the respective receptacles.

Signed by me this 3d day of December, 1903.

MARY A. BROWN.
